CLAIM

I claim the ornamental design for a dual chambered baby bottle, as shown and described.

DESCRIPTION

FIG. 1 is an exploded side perspective view of a dual chambered baby bottle showing my new invention.

FIG. 2 is a side perspective view of thereof, shown in an assembled condition.

FIG. 3 is an exploded side cross-sectional view taken along line 3—3 of FIG. 2.

FIG. 4 is a side cross-sectional view taken along line 4—4 of FIG. 2; and,

FIG. 5 is an exploded side perspective cross-sectional view taken along line 5—5 of FIG. 2.

The broken lines illustrate environmental components of the dual chambered baby bottle and form no part of the claimed design.
